TITLE SET TOOL

Valentine Pizzani, New York, N. Y.

Application July 27, 1950, Serial No. 176,187

5 Claims. (Cl. 72—128)

1

The present invention relates to improvements in tile setting equipment, and more particularly to a tool for holding tiles preparatory to setting the same.

An object of the present invention is to provide a means whereby a plurality of tiles may be positioned on a tool and aligned, spaces being provided between the tiles, whereby the plurality of tiles may be provided with cement preparatory to positioning the tile on a wall or the like.

Another object of the present invention resides in the means whereby the plurality of tiles are adjustably held, thereby permitting the edges of the individual tiles to be aligned for accurate setting.

Still another object of the present invention is to provide a novel handle arrangement whereby the tile setting tool may be supported while positioning the tiles on the face of the tool preparatory to adjustably holding the same.

This invention also comprises novel details of construction and novel combinations and arrangements of parts which will more fully appear in the course of the following description. However, the drawings merely show and the following description merely describes an embodiment of the present invention which is given by way of illustration or example only.

In the drawings:

Figure 1 is a perspective view of the back side of the tile setting tool;

Figure 2 is a top plan view showing the back side of the tile setting tool;

Figure 3 is a vertical longitudinal sectional view taken substantially along the plane of line 3—3 of Figure 2;

Figure 4 is a perspective view of the face of the tile setting tool with a plurality of tile mounted therein;

Figure 5 is a view of a portion of the face of the tile setting tool, parts being broken away;

Figure 6 is a detail perspective view of the holding member of the present invention;

Figure 7 is a side elevational view showing the tile setting tool supported on its handle; and

Figure 8 is a detail view of a portion of the tile setting plate with part in section.

Referring more particularly to the drawings, wherein like numerals designate like parts throughout, the numeral 10 designates generally the tile setting plate of the present invention, the numeral 12 designates generally the handle structure associated with the tile setting plate 10, the numeral 14 designates generally the holding means for releasably clamping the tiles in

2

their predetermined relation, and the numeral 16 designates generally the spacing means which is adjustably positioned on the base of the tile setting plate 10.

5 The tile setting plate 10 may be formed of wood, other material being used if desired, and the peripheral edge of the tile setting plate 10 is recessed on its back side at 18 and on its outside edges at 20. Brass angle plates 22, 24, 26 and 28 are inserted in the recesses 18 and 20 and secured therein by means of screws 30. The plate 10 is provided with an elongated, substantially rectangular opening 32 for a purpose to be hereinafter described. The face 34, upon which the tiles are positioned, is formed with a plurality of spaced and transversely extending recesses 36. The recesses 36 are provided with recessed extensions 38 which are of non-circular form for receiving the nuts 40 for a purpose to be hereinafter set forth.

10 On the back side 42 of the tile setting plate 10, the handle 12 is positioned at 44. The handle 12 is of substantially bar form and is provided with an angulated cut 46 at its outer end which is adapted to engage a supporting surface.

15 The spacing means 16 includes a pair of retaining guide pins 48 which are positioned in each of the pairs of recessed extensions 38. The inner ends of the pins 48 are threaded in order that the pins may be threadably engaged in the nuts 40. The outer ends of the pins 48 are provided with enlarged disk heads 50, providing a retaining means. The nuts 40 and guide retaining pins 48 are held within the recesses of the face of the tile setting plate 10 by means of the retaining plates 52 which are held within the elongated recesses 36 by means of screws 54.

20 A plurality of elongated spacer elements 56, at 16 in Figure 5, are formed with elongated slots 58 for receiving the guiding retaining pins 48 and whereby the enlarged heads 50 are adapted to retain the spacers 56 within the recesses 36. The spacer elements 56 are provided with downwardly projecting angulated portions 60 which are adapted to be positioned between the tiles 62 for spacing the same.

25 The holding means 14 includes a bracket 64 which is secured to the back side 42 of the tile setting plate 10 by means of screws 66. A central portion of the bracket 64 is enlarged at 68 and is provided with an internally threaded bore 70. An angulated holding member 72 is positioned in the elongated recess 74 in the back side of the plate 10 for reciprocable movement therein. The member 72 is provided with two

angulated portions, the first angulated portion 76 extending through the opening 32 for engagement with the end 78 of one of the tiles 62. The other end of the member 72, the second angulated portion 80, is in upstanding vertical relation to the back side 42 of the plate 10. A threaded lug 82 is threadably positioned within the bore 70 of the bracket 64 and has a knurled handle portion 84 at one end. The other end of the lug 82 is provided with an enlarged head 86 which is secured thereon by means of the pin 88 and which engages the second angulated portion 80 of the member 72.

As seen best in Figure 6, the holding member 72 is provided on its first angulated portion 76 with an elongated tile engaging portion 90 which is adapted to engage the face 78 of the end tile 62.

From the foregoing description, taken in conjunction with the drawings, it is believed that one skilled in the art will readily understand the manner in which the tile setting tool of the present invention is employed. Although the form shown provides means for setting five tiles in position, it should be noted that the tile setting tool could be formed to accommodate any number of tiles which are of any size and shape.

A plurality of tiles 62 are positioned on the face 34 of the plate 10 when the tile setting tool is in the position shown in Figure 7. Each of the spacing means has the portion 60 positioned between the ends of the tiles 62. The entire tool is lifted by means of the handle 12 and the knurled handle 84 is rotated until the first angulated portion 76 and the tile engaging portion 90 engage the end tile 62. By moving the member 72 a little farther, all of the tiles engage the spacing means positioned therebetween and move the same until all of the tiles are held together with a predetermined degree of firmness. The whole tool is then held on its side so that the side edges of the tiles 62 may be tapped against a flat surface such as a flat board for aligning the tiles. Then the knurled handle is rotated until the tiles are firmly clamped in place and the conventional tile cementitious substance is applied to the bases of the tiles. The tile setting tool is then ready to be employed for positioning the tiles on a wall or the like.

Some changes may be made in the construction and arrangement of the parts of my device without departing from the real spirit and purpose of my invention, and it is my intention to cover by my claims any modified forms of structure or use of mechanical equivalents which may be reasonably included within their scope without sacrificing any of the advantages thereof.

Having thus described the invention, what is claimed as new is:

1. A tile setting tool comprising an elongated holding plate, a plurality of tile spacing means individually adjustably positioned on the face of said plate for spacing a plurality of tiles in predetermined relation to each other, and holding means for releasably clamping the tiles in the predetermined relation, said holding means including an angulated holding member, an opening in said plate through which an angulated portion of said member projects, said angulated member being reciprocably guided in a groove on the back side of said plate, and means for adjustably moving said member whereby said angulated portion engages one of the tiles and urges it toward the other tiles, effecting adjustment of said spacing means and clamping of the tiles.

2. A tile setting tool comprising an elongated

holding plate, a plurality of tile spacing means individually adjustably positioned on the face of said plate for spacing a plurality of tiles in predetermined relation to each other and holding means for releasably clamping the tiles in the predetermined relation, said holding means including an angulated holding member, an opening in said plate through which an angulated portion of said member projects, said angulated member being reciprocably guided in a groove on the back side of said plate, means for adjustably moving said member whereby said angulated portion engages one of the tiles and urges it toward the other tiles, effecting adjustment of said spacing means and clamping of the tiles, said last-named means including an internally threaded and apertured bracket on said back side, a threaded lug adjustably receivable in said apertured bracket, and an end portion of said lug engageable with a second angulated portion of said member for movement thereof.

15 3. A tile setting tool comprising an elongated holding plate, a plurality of tile spacing means individually adjustably positioned on the face of said plate for spacing a plurality of tiles in predetermined relation to each other, and holding means for releasably clamping the tiles in the predetermined relation, said spacing means including an internally threaded and apertured bracket on said back side, a threaded lug adjustably receivable in said apertured bracket, and an end portion of said lug engageable with a second angulated portion of said member for movement thereof.

20 4. A tile setting tool comprising an elongated holding plate, a plurality of tile spacing means individually adjustably positioned on the face of said plate for spacing a plurality of tiles in predetermined relation to each other, and holding means for releasably clamping the tiles in the predetermined relation, said spacing means including an internally threaded and apertured bracket on said back side, a threaded lug adjustably receivable in said apertured bracket, and an end portion of said lug engageable with a second angulated portion of said member for movement thereof.

25 5. A tile setting tool comprising an elongated holding plate, a plurality of tile spacing means individually adjustably positioned on the face of said plate for spacing a plurality of tiles in predetermined relation to each other, and holding means for releasably clamping the tiles in the predetermined relation, said spacing means including an internally threaded and apertured bracket on said back side, a threaded lug adjustably receivable in said apertured bracket, and an end portion of said lug engageable with a second angulated portion of said member for movement thereof.

30 6. A tile setting tool comprising an elongated holding plate, a plurality of tile spacing means individually adjustably positioned on the face of said plate for spacing a plurality of tiles in predetermined relation to each other, and holding means for releasably clamping the tiles in the predetermined relation, said spacing means including an internally threaded and apertured bracket on said back side, a threaded lug adjustably receivable in said apertured bracket, and an end portion of said lug engageable with a second angulated portion of said member for movement thereof.

35 7. A tile setting tool comprising an elongated holding plate, a plurality of tile spacing means individually adjustably positioned on the face of said plate for spacing a plurality of tiles in predetermined relation to each other, and holding means for releasably clamping the tiles in the predetermined relation, said spacing means including an internally threaded and apertured bracket on said back side, a threaded lug adjustably receivable in said apertured bracket, and an end portion of said lug engageable with a second angulated portion of said member for movement thereof.

40 8. A tile setting tool comprising an elongated holding plate, a plurality of tile spacing means individually adjustably positioned on the face of said plate for spacing a plurality of tiles in predetermined relation to each other, and holding means for releasably clamping the tiles in the predetermined relation, said spacing means including an internally threaded and apertured bracket on said back side, a threaded lug adjustably receivable in said apertured bracket, and an end portion of said lug engageable with a second angulated portion of said member for movement thereof.

45 9. A tile setting tool comprising an elongated holding plate, a plurality of tile spacing means individually adjustably positioned on the face of said plate for spacing a plurality of tiles in predetermined relation to each other, and holding means for releasably clamping the tiles in the predetermined relation, said spacing means including an internally threaded and apertured bracket on said back side, a threaded lug adjustably receivable in said apertured bracket, and an end portion of said lug engageable with a second angulated portion of said member for movement thereof.

50 10. A tile setting tool comprising an elongated holding plate, a plurality of tile spacing means individually adjustably positioned on the face of said plate for spacing a plurality of tiles in predetermined relation to each other, and holding means for releasably clamping the tiles in the predetermined relation, said spacing means including an internally threaded and apertured bracket on said back side, a threaded lug adjustably receivable in said apertured bracket, and an end portion of said lug engageable with a second angulated portion of said member for movement thereof.

55 11. A tile setting tool comprising an elongated holding plate, a plurality of tile spacing means individually adjustably positioned on the face of said plate for spacing a plurality of tiles in predetermined relation to each other, and holding means for releasably clamping the tiles in the predetermined relation, said spacing means including an internally threaded and apertured bracket on said back side, a threaded lug adjustably receivable in said apertured bracket, and an end portion of said lug engageable with a second angulated portion of said member for movement thereof.

60 12. A tile setting tool comprising an elongated holding plate, a plurality of tile spacing means individually adjustably positioned on the face of said plate for spacing a plurality of tiles in predetermined relation to each other, and holding means for releasably clamping the tiles in the predetermined relation, said spacing means including an internally threaded and apertured bracket on said back side, a threaded lug adjustably receivable in said apertured bracket, and an end portion of said lug engageable with a second angulated portion of said member for movement thereof.

65 13. A tile setting tool comprising an elongated holding plate, a plurality of tile spacing means individually adjustably positioned on the face of said plate for spacing a plurality of tiles in predetermined relation to each other, and holding means for releasably clamping the tiles in the predetermined relation, said spacing means including an internally threaded and apertured bracket on said back side, a threaded lug adjustably receivable in said apertured bracket, and an end portion of said lug engageable with a second angulated portion of said member for movement thereof.

70 14. A tile setting tool comprising an elongated holding plate, a plurality of tile spacing means individually adjustably positioned on the face of said plate for spacing a plurality of tiles in predetermined relation to each other, and holding means for releasably clamping the tiles in the predetermined relation, said spacing means including an internally threaded and apertured bracket on said back side, a threaded lug adjustably receivable in said apertured bracket, and an end portion of said lug engageable with a second angulated portion of said member for movement thereof.

75 15. A tile setting tool comprising an elongated holding plate, a plurality of tile spacing means individually adjustably positioned on the face of said plate for spacing a plurality of tiles in predetermined relation to each other, and holding means for releasably clamping the tiles in the predetermined relation, said spacing means including an internally threaded and apertured bracket on said back side, a threaded lug adjustably receivable in said apertured bracket, and an end portion of said lug engageable with a second angulated portion of said member for movement thereof.

80 16. A tile setting tool comprising an elongated holding plate, a plurality of tile spacing means individually adjustably positioned on the face of said plate for spacing a plurality of tiles in predetermined relation to each other, and holding means for releasably clamping the tiles in the predetermined relation, said spacing means including an internally threaded and apertured bracket on said back side, a threaded lug adjustably receivable in said apertured bracket, and an end portion of said lug engageable with a second angulated portion of said member for movement thereof.

85 17. A tile setting tool comprising an elongated holding plate, a plurality of tile spacing means individually adjustably positioned on the face of said plate for spacing a plurality of tiles in predetermined relation to each other, and holding means for releasably clamping the tiles in the predetermined relation, said spacing means including an internally threaded and apertured bracket on said back side, a threaded lug adjustably receivable in said apertured bracket, and an end portion of said lug engageable with a second angulated portion of said member for movement thereof.

90 18. A tile setting tool comprising an elongated holding plate, a plurality of tile spacing means individually adjustably positioned on the face of said plate for spacing a plurality of tiles in predetermined relation to each other, and holding means for releasably clamping the tiles in the predetermined relation, said spacing means including an internally threaded and apertured bracket on said back side, a threaded lug adjustably receivable in said apertured bracket, and an end portion of said lug engageable with a second angulated portion of said member for movement thereof.

95 19. A tile setting tool comprising an elongated holding plate, a plurality of tile spacing means individually adjustably positioned on the face of said plate for spacing a plurality of tiles in predetermined relation to each other, and holding means for releasably clamping the tiles in the predetermined relation, said spacing means including an internally threaded and apertured bracket on said back side, a threaded lug adjustably receivable in said apertured bracket, and an end portion of said lug engageable with a second angulated portion of said member for movement thereof.

100 20. A tile setting tool comprising an elongated holding plate, a plurality of tile spacing means individually adjustably positioned on the face of said plate for spacing a plurality of tiles in predetermined relation to each other, and holding means for releasably clamping the tiles in the predetermined relation, said spacing means including an internally threaded and apertured bracket on said back side, a threaded lug adjustably receivable in said apertured bracket, and an end portion of said lug engageable with a second angulated portion of said member for movement thereof.

termined relation to each other, and holding means on said plate for clamping the tiles in their predetermined relation.

VALENTINE PIZZANI.
